FLUID HEATER

Joseph W. Bouldin, Los Angeles, Calif.

Application June 25, 1945, Serial No. 601,489

6 Claims. (Cl. 122—17)

The invention relates to a fluid heater and more particularly to a water heater.

An object of the invention is to provide a fluid heater which is simple in construction and which makes efficient use of the source of heating such as a gas flame. This is accomplished by employing a fire tube type of heating unit arranged in a vertical position and provided with an outer casing to provide a flue space around the heating unit. Preferably the heating unit is provided with a bulging top wall and a bulging bottom wall which contribute to efficient heating in the following way.

The bulging bottom wall provides an extended surface against which the flame of the burner is directed and as this surface increases in radius in an upward direction it guides that part of the heated gas which does not flow through the fire tube, to the side wall of the heating unit. The bulging top wall also is an extended surface which is utilized for further heating the fluid, through the use of a cooperating cast iron or thick metal cap spaced therefrom and cooperating therewith to provide a flue space at the top of the heating unit. As the heavy metal cap forms one wall of the upper portion of the flue which is heated by the gases from the burner, it thereby becomes heated and heats the extended top wall of the heating unit by convection. It also directs or reflects the hot gases on the top wall. A suitable heat insulating jacket is provided around the heating unit.

In the preferred form of the invention the side wall as well as the top and bottom of the heating unit are provided with a spaced cast iron or other heavy metal outer flue member in heat exchange and reflecting relation to the side wall and both end walls of the heating unit.

A further object of the invention is to employ a fire tube type of heating unit in a vertical position whereby it directs the heated gases from the burner upwardly to a flue, with the provision of bulging top and bottom walls on the heating unit whereby the heated gases from the burner heat not only the fire tubes but also the side wall and both end walls with the flame directly heating the bottom wall, and with the further provision of a heat radiating jacket forming an outer flue member in heat exchange relation to some part or all of the heating unit.

For further details of the invention reference may be made to the drawings wherein Fig. 1 is a vertical sectional view of a fluid heater according to the present invention.

Fig. 2 is a similar view of a preferred form of the invention.

Referring in detail to the drawings, the fluid heater 1 of this invention comprises a heating unit 2 having a cylindrical side wall 3 and bulging top and bottom walls 4 and 5, here illustrated as dome-shaped and conical respectively. The axis of the heating unit 2 is vertical and enclosed by the side wall 3 is a plurality of vertical fire tubes 6 such as indicated at 7 which open at their outer ends in an intermediate portion of the end walls 4 and 5 as indicated at 8. Below the bottom wall 5 is arranged a gas burner 9 preferably having jets arranged on a plurality of steps 10, 11 and 12 which lie on a conical surface parallel to the conical surface of the bottom wall 5. The burner 9 is preferably arranged close enough to the bottom wall 5 so that the flame of the burner is directed against the bottom wall 5. Around the heating unit 2 is an inner sheet metal casing 13 and spaced therefrom an outer sheet metal casing 14 with a packing 15 of insulating material therebetween. The bottom of the casings 13 and 14 is supported by a ring-shaped base 16 having a vertical flange 17 to which the casings 13 and 14 are secured by stove bolts 18. The base 16 has suitable legs 19 secured thereto by bolts 20. The base 16 has an opening 21 large enough to pass the heating unit 2.

The burner 9 is held in position by a bracket 22 secured by a stove bolt 23 to the inside of casing 13 and by the gas supply pipe 24 which passes through the casings 13 and 14.

Extending parallel to and spaced from the top wall 4 is a cast iron cap 25 having a vertical flue 26 which passes through a central opening 27 in a cover 28 secured by bolts 29 to the top of casings 13 and 14. Cap 25 is secured to casing 13 by bolts 32.

The hot water or other fluid is stored in a tank 30 having a cold water connection 31 to the bottom of the heating unit 2 as indicated at 32. Tank 30 has a hot water connection 33 connected to the center of the top wall 4 as indicated at 34, the connection 33 passing through and being supported by casings 13 and 14 and flue 26 as indicated at 35 and 36 respectively. The side wall 3 is further supported by the clean out connection 37 which passes through and is supported by casings 13 and 14 as indicated at 38 and by a connection 39 which similarly passes through and is supported by casings 13 and 14 as indicated at 40.

A thermometer not shown may be used with connection 39 to determine when the scale in the unit 2 needs to be removed by passing a suitable

boiler cleaning compound in the clean out connection 37. A drain connection is indicated at 41.

As above explained, efficient heating flows from the fact that the heating unit 2 is arranged in a vertical position and serves in effect as an inner flue member to direct the heated gases from burner 9 upwardly and around the bulging ends and side walls of the unit as well as through the fire tubes 6. Also the burner 9 directly heats the bottom wall 5. Also some of the heat in the gases is absorbed by the cap 25 and radiated therefrom to the top wall 4, and cap 25 reflects or directs the hot gases onto the top wall 4.

The preferred form of the invention is shown in Fig. 2 wherein the fluid heater 42 comprises a heating unit 43 which is upside down from that shown in Fig. 1, whereby the bottom wall 44 is dome shaped and the top wall 45 is conical. A burner 46 is arranged beneath the bottom wall 44 and is provided with pairs of jets such as 47 and 48 which are directed towards each other, the resulting flame impinging directly on the bottom wall 44. All of the jets such as 47 and 48 are on the same level. Around the heating unit 43 and extending from the top of the side wall 49 to the ring base 50 is a cylindrical cast iron jacket 51 which serves as an outer flue member to absorb heat and radiate it to the side wall 49 and the bottom 44 of the heating unit and direct or reflect the hot gases against the heating unit. The jacket 51 has an inturned flange 52 secured to the ring 50 by bolts 53. Inside of the jacket 51 is arranged a number of brackets such as 54 secured to the jacket 51 by bolts 55. The brackets like 54 support the outer edge of the bottom wall 44. Resting on the jacket 51 is a cast iron cap 56 secured thereto by bolts 57. Cap 56 extends parallel to and spaced from the conical top 45 to provide another portion of a flue for the heated gases from burner 45. Cap 56 has a central vertical flue 58 which passes through an opening 59 in a cover 60. Cover 60 rests on a sheet metal casing 61 which is cylindrical and larger than the jacket 51, the intervening space between casing 61 with its cover 60 and jacket 51 with its cap 56 being filled with a packing of insulating material 62. Cover 60 is secured to the top of casing 61 by bolts 63 and the bottom of casing 61 is secured to a flange 64 arising from base 59, by bolts 65. The cold connection 66 is piped into the bottom of the side wall 49 and the hot connection 67 is taken from the truncated top 68 of the top wall 45. The hot water is concentrated at the hot connection 67 by reason of the fact that the top wall 45 tapers in to the hot connection 67, also the surface of the conical top 45 and the cap 56 are more extended than if the heating unit were inverted as in Fig. 1. Also the cylindrical jacket 51 increases the thermal efficiency through absorbing heat from the hot gases and radiating it to the heating unit, and directing or reflecting the hot gases on the heating unit. Also the jacket 51 in combination with the pipe connections 66, 69 and 70 and 67 assist the

brackets 54 in supporting the heating unit 43 in a vertical position concentric with the jacket 51. As previously described, ring base 50 has an opening 71 through which the unit 43 may be inserted after the jacket 51 and casing 61 are bolted to the base 50, although the unit 43 may be assembled in position shown by inserting it in the top of jacket 51 and casing 61 if desired.

It will be apparent that various modifications may be made in the invention without departing from the spirit of the following claims.

I claim:

1. A fluid heater comprising a vertical heating unit having a cylindrical side wall and bulging top and bottom walls, vertical flue pipes surrounded by said side wall and opening through an intermediate portion of said top and bottom walls, a burner disposed beneath said bottom wall and adapted to direct flames on said bottom wall, a casing around and spaced from said side wall and providing a flue space for said burner along said side wall, a thick metal cap for said casing, said cap extending substantially parallel to and spaced from said bulging top wall to form a continuation of said first mentioned flue space, said cap at its upper end having a flue opening, and a fluid inlet and a fluid outlet for said unit.
2. A fluid heater according to claim 1 wherein one of said bulging walls is conical and the other dome shaped.
3. A fluid heater according to claim 1 wherein pipe connections for said inlet and for said outlet are connected to said side wall and support said heating unit in said casing.
4. A fluid heater according to claim 1 wherein said top wall is conical and said bottom wall is dome shaped, said casing comprising an inner casing of thick metal, a sheet metal outer casing, a packing of insulating material between said outer casing and said inner casing and cap, a base ring supporting said inner and outer casings, said ring having a central opening larger than the periphery of the side wall of said unit, and brackets secured inside said inner casing and supporting said heating unit above said burner and above said base ring.
5. A fluid heater comprising a vertical heating unit having a side wall and bulging top and bottom walls, vertical flue pipes surrounded by said side wall and opening through an intermediate portion of said top and bottom walls, means providing a flue space around said side wall and over said top wall, a burner beneath said bottom wall in heating relation to said bottom wall, said flue pipes, said side wall and said top wall, a cold fluid inlet adjacent the bottom of said unit, and a heated fluid inlet at the top of said top wall.
6. A fluid heater according to claim 5 wherein said means comprises a cast iron cylindrical inner casing and a cast iron cap therefor having a flue, an outer sheet metal casing, a cover for said sheet metal casing having a central opening for said cap flue, and a packing of insulating material between said outer casing with its said cover, and said inner casing with its said cap.

JOSEPH W. BOULDIN.
